Primary Examiner — Natasha Vujcic(74) *Attorney, Agent, or Firm* — LaMorte & Associates
PC(57) **CLAIM**

The ornamental design for a lighting apparatus with electrical junction box as shown and described.

DESCRIPTION

FIG. 1 is a top view of a lighting apparatus with electrical junction box;

FIG. 2 is a bottom view thereof;

FIG. 3 is a front view thereof;

FIG. 4 is a rear view thereof;

FIG. 5 is a left side view thereof;

FIG. 6 is a right side view thereof; and,

FIG. 7 is a perspective view thereof.

The broken lines in the drawings illustrate portions of the lighting apparatus with electrical junction box and form no part of the claimed design.
